APPARATUS FOR CONDITIONING MATERIAL

Elmer C. Ingraham, Hampstead, N. H.

Application March 5, 1932, Serial No. 597,043

7 Claims. (Cl. 261—119)

The present invention relates to an apparatus for conditioning material and has special application to the mulling of leather used in the manufacture of shoes.

5 Mulling boxes of the type now in use are subject to certain limitations and objections, for example, their bulk for a given holding capacity of shoe parts is excessive, an operative is required to enter the box to load and unload the same, the mulling action effected thereby is not uniform chiefly because the humidified air is forced into contact with the leather to be treated and the resulting frictional contact between such air and material exerts a drying influence, and 10 their first cost, as well as the cost of operation and servicing, is prohibitively high.

The object of the present invention, generically speaking, is to provide an apparatus for conditioning material, whereby the aforesaid 15 limitations and objections are overcome, and, specifically, to improve and simplify the mulling boxes of the prior art to increase the efficiency thereof.

With this object in view, my invention involves 20 an apparatus for conditioning material such as leather and fabrics used in the manufacture of shoes comprising means for humidifying air and for allowing the moisture carried by the air so humidified to diffuse uniformly into said material 25 while eliminating frictional contact between the humidified air and material, whereby uniform mulling action is secured. The humidification of the air may be continuous and is effected, preferably, in a closed chamber containing the 30 material to be treated, and I prefer to rehumidify 35 the air after a portion of the moisture carried thereby has been diffused into the material.

My invention involves also the use of a chamber, preferably cylindrical, having a hollow 40 member affording a duct, which may be centrally-disposed and terminates short of opposite walls of the chamber, any suitable air-humidifying means, such as an open liquid-container of substantial surface area disposed in 45 the vicinity of said duct and preferably co-axial therewith, and a low-power impeller arranged in co-operative relation with said duct and container, whereby a continuous circulation of humidified air is created steadily, slowly and gently, or without force, through said duct so that 50 the conditioning gas or vapor is allowed to diffuse evenly through the chamber and into the material supported therein without any frictional contact between the humidified air and 55 said material.

In the preferred form of my invention there is maintained in the chamber a curtain of moving humidified air adjoining and, preferably surrounding the space occupied by the material and from which vapor diffuses into such space and thence into said material. The diffusion of such vapor from the humidified air through the chamber and into the material to be treated without frictional contact between said humidified air and material, as distinguished from forcibly 10 directing a blast of such humidified air into contact with said material, is the salient feature of my invention because thereby the drying action or influence aforesaid is eliminated and the mulling of such material is rendered absolutely uniform.

Preferably means such as an electrical heating unit are provided for raising the temperature of the liquid, for example, water, with which said container is filled, and in such case, the heating 20 unit may be placed in an inlet pipe, so arranged with respect to an outlet pipe that slow circulation of heated liquid around the container is induced. The aforesaid duct preferably is mounted for rotation and provided with material-supporting means, such as laterally-extending hangers or shelves whereby the material undergoing treatment is carried, and the vertical wall of the chamber is provided with a 25 door through which the material may be placed into and removed from the chamber. Means, such as a pocket or gutter, may be provided for receiving the liquid condensation of vapor formed on the upper wall of the chamber and for conducting the same to the exterior of the chamber, or else for returning such liquid condensation to the liquid container, thereby 30 keeping the inner walls of the chamber dry and preventing liquid from coming into contact with the material to be conditioned. The top closure of the chamber, preferably is provided with a flange constructed and arranged to take into 35 said pocket or gutter which may be formed between the inner and outer walls of the chamber and into which the said liquid condensation is received to make an air-tight or water-sealed joint between said top closure and chamber, and from which any overflow may be conducted to the exterior of the chamber or to the liquid container, as desired.

In order to prevent any direct impact of humidified air against the material undergoing treatment, I may, if necessary, employ a baffle extending from the lower end of said duct out-

wardly toward, but terminating short of, the vertical wall of the chamber.

The bottom of the chamber preferably is provided with a drain for carrying off the liquid overflow from the container, as well as the contents of said container when the latter is emptied for cleaning the same.

Thermostatic and time-control devices may be employed in connection with my improved 10 mulling box for the same purposes for which such devices have long been used in various other arts.

Various other details of construction, parts and combination of parts which make up my 15 invention will be hereinafter more fully described and set forth in the appended claims.

My invention will be described in connection with the accompanying drawings illustrating apparatus which have given good results in practice, but it is to be understood that said drawings are to be considered as illustrative merely and not restrictive.

In the drawings,—

Figure 1 is a central vertical section of an 25 apparatus for conditioning material, specifically, a mulling box for shoe uppers, which embodies my invention;

Fig. 2 is a similar section on an enlarged scale taken on a plane angularly related to that on 30 which the section shown in Fig. 1 is taken;

Fig. 3 is a transverse section taken on the line 3—3 of Fig. 1;

Fig. 4 is a central vertical section of a modification.

In the particular drawings selected for more 35 fully disclosing my method and the apparatus whereby the same may be carried out, 10 is a cylindrical chamber, preferably double-walled and heat-insulated by a packing of mineral wool 40 11, said chamber having a fixed bottom or base-plate 12 and a removable top closure 13. Secured to the upper portion of the chamber or mulling box in any suitable manner, is an open liquid-container 14, herein shown as a flat pan having 45 a depressed or conical bottom 15 and provided with a centrally-disposed collar 16, the upper plane of which is slightly lower than the plane of the upstanding rim 17 of the pan. However, 50 a humidifier of any other suitable type may be used.

For stiffening the pan or container, an upwardly-directed conical member 18 is connected to 55 said collar 16 and is provided with an upstanding rim 19 overlapping and suitably secured to the rim of the pan. In the present instance the pan 14 is held in position by several straps 20, attached at their lower ends to the rim of the member 18, and terminating in hooks 21 taking over the upper edge of the inner wall of the chamber. 60 Any suitable means such as the braces 22 and 23 may be provided to facilitate the positioning and assist in further strengthening the structure, respectively.

Disposed within the chamber centrally as 65 shown, is a hollow member 24 affording a duct or canal, said member being mounted for rotation on the spindle 25, the lower end of which is provided with a thrust bearing 26 and its upper end with the journal 27 supported within the collar 16 by the spider 28. It is to be understood however that any suitable means may be employed to mount said duct rotatably within the chamber. The duct preferably is provided with laterally-extending hangers for supporting 70 the material to be treated, and in the present

instance, said hangers 29, 29 are suitably secured to the spindle and project through the duct, thus affording a convenient means for rotating the spindle and with it, the duct, to bring any desired set of hangers in position for loading or unloading. 5

The top closure of the chamber is shown in the present instance as consisting of the upwardly-directed conical member 29' and the stiffening disc 30, both of which are suitably attached to the cylindrical rim or flange 31 which extends into the pocket or gutter 32 formed between the inner and outer walls of the chamber by securing between said walls near the top thereof the U-shaped member 33, the said rim 31 abutting and closely fitting the outer wall of the chamber and the water or other liquid formed in said pocket by condensation on the top closure, as hereinafter more fully explained, effecting an air-tight or water-sealed juncture between said closure and said chamber. When operating the apparatus for the first time a small quantity of liquid may be placed in said gutter.

Disposed above the upper end of the duct is an impeller 34 driven by a motor 35 of relatively 25 low power, for example, one-twentieth horsepower, the said motor and impeller being mounted on the disc 36, preferably corrugated for strength, and said disc being removably secured to the top closure in any suitable manner as, for 30 example, by the wing-nuts 37. For convenience in handling the motor and impeller, a bail 38 having its feet riveted to the disc 36, is provided.

While various means may be employed for heating the water, or other suitable liquid in 35 the container 14, I prefer to employ an electrical heating unit 39 disposed in the inlet pipe 40 which enters said container at a point near the collar 16 where the depth of liquid therein is greatest. Connected with the lower end of said inlet pipe 40 and entering the container in the same plane as the pipe 40 is an outlet pipe 41, the said pipes being shown in the present instance as terminating in divergent ends directed toward the periphery of the container, as shown in Fig. 3, so 45 that a slow circulatory movement of heated liquid is induced in the latter, and such movement is assisted by the air current created by the impeller. It will be understood of course that the ends of said pipes need not be divergent and that 50 it is necessary only that they be spaced part. A pipe 42 may be provided for filling the container, and in the event of accidental overflow from the latter, the excess liquid flows over the edge of the collar 16 which, as aforesaid, is slightly lower 55 than the plane of the upper edge of said container, and down through the duct to the bottom of the chamber whence it is carried away by the drain 43. When it is desired to empty the liquid container, the normally-closed valve 44 is opened 60 and the water or other liquid flows through the pipes 40, 41 and the extension 45 thereof to the base of the chamber whence it is carried away by said drain.

The use of heated vapor for mulling shoe parts 65 or other materials is not new but, as above stated, the mulling action effected by the devices now in use, is not uniform, chiefly because they involve means for forcibly directing humidified air into contact with the material to be treated. 70

The salient feature of the present invention consists in so arranging matters that no humidified air is forcibly directed against the material to be conditioned but, on the contrary, the vapor is allowed to diffuse spontaneously and naturally. 75

and without force, through the space in which the material is hung and into said material, thereby effecting uniform mulling. By means of the small motor 35, which requires only a fraction 5 of an electrical horsepower for its operation, air within the chamber, as indicated by the arrows in Fig. 1, is continuously re-circulated through the duct and along the surface of the liquid in the container 14, thereby humidifying the same, 10 and from said air so humidified the vapor diffuses through the space between the duct and the walls of the chamber in which the material is hung, and into said material.

It is well known that frictional contact between air and material exerts a drying influence 15 or action on such material, and I have discovered in the practice of this art that no matter what the degree of the humidity of the air may be, the said drying influence is exerted whenever there 20 is frictional contact between the air and the material to be treated and that, therefore, uniform and efficient results cannot be obtained when the moistened air is forcibly directed into contact with the material. My invention therefore involves means for effecting the diffusion of moisture 25 into the air enclosed within the chamber 10, means for allowing the moisture to diffuse uniformly into the material supported in said chamber without permitting any frictional contact 30 between the moistened air and material, but carefully eliminating the same, and preferably means for replacing into the air the moisture that was removed therefrom by diffusing into the material. This is accomplished by the design and 35 arrangement of the parts to obtain a curtain of moving humidified air adjoining, or as shown in the preferred embodiment of my invention surrounding, the space occupied by the material being treated, from which curtain of humidified air the vapor diffuses uniformly into the space occupied 40 by the material and thence into the material itself. To further guard against any possibility of frictional contact between the moistened or humidified air and the material caused by the forcible direction of humidified air 45 against such material, I may provide necessary baffles such as the baffle 47 located at the lower end of the duct and extending toward, but terminating short of, the cylindrical wall of 50 the chamber, said baffle being supported on the base of the chamber in any suitable manner, as for instance, by the brackets 48. It is to be understood that said baffle is not always necessary as for example, when the material is disposed 55 on the laterally-extending shelves hereinbefore mentioned, but its use is sometimes needed to avoid any direct current of air or short-circuit from the space or passage between the pan 14 and the inner wall of the chamber directly to 60 the lower end of the duct when the material is suspended as by the hangers 29.

It will be noted that after the humidified air has been passed by the space in which the material is disposed for treatment, the impeller 65 draws the same upwardly through the duct and then causes the same to pass again over the pan in contact with the liquid therein for further humidification to replace the vapor content thereof which was absorbed by said material. While the 70 impeller has been described as a fan for drawing a current of the humidified air upwardly through the duct, it is to be understood that by properly arranging matters, the current of humidified air may be directed downwardly through said duct 75 and upwardly through the space between the

liquid-container and the wall of the chamber and then across the pan to the upper end of the duct. In either event, there may be a slow circulation of heated vapor or humidified air through the space in which the material is hung, but in neither case is such humidified air or vapor directed forcibly into contact with said material.

The water in the pan 14, not being heated in contact with the upper wall 29' of the chamber and said upper wall or top closure not being heat-insulated, it follows that there will be a certain amount of condensation of moisture on said upper wall which will drip into the circumferential pocket 32 and form an air-tight or water-sealed joint between the flange 31 of the top-closure and the outer wall of the chamber 10. To prevent overflow of the liquid in said pocket down the cylindrical walls of the chamber, I may provide a conduit 49 connecting the upper portion of said pocket to the pan 14 and inclined downwardly 20 toward the latter.

The thermostatic and time-control devices that govern the temperature and regulate the periods of operation of the mulling box, respectively, may conveniently be enclosed in the casing 50 secured 25 to the exterior wall of the chamber.

Referring to Fig. 4 which shows a modified form of mulling box whereby my method may be realized in practice, the duct 24 extends to the base 12 which is provided with a series of apertures 51 disposed, preferably, circumferentially with respect to the axis of the spindle 25 and lying within that portion of said base with which the end of the duct makes contact. The base is provided also with a series of apertures 52, also disposed 30 circumferentially with respect to the axis of the spindle and located in that portion of the base between the baffle 47 and the inner wall of the chamber.

The operation is identical with that hereinbefore set forth with respect to Fig. 1, with the exception that air from without the chamber is drawn through the apertures 51 into the duct and thence along the surface of the liquid in the pan, thereby humidifying the same, and after the 45 humidified air has been passed by the space in which the material is disposed for treatment, it passes out of the chamber through the apertures 52, and does not again pass over the pan in contact with the liquid therein for further humidification. The apparatus shown in Fig. 1, however, is the preferred form of my invention because thereby there is replaced into the air the moisture that was lost by diffusion into the material, and a higher degree of humidification is 55 maintained, with the result that the mulling action is expedited and complete mulling effected in less time than is possible without rehumidification.

Instead of returning the liquid condensation which accumulates in the gutter 32 to the pan in the manner above described in connection with Fig. 2, I may provide a pipe 53, as shown in Fig. 4, disposed between the inner and outer walls of the chamber and having its upper end terminating below the top of said pocket, whereby the liquid in said pocket is maintained at sufficient depth to effect the water seal between the top closure and the chamber, and the surplus will be conveyed through said pipe to the pocket 54 formed between the inner and outer wall of the chamber 60 by the inverted U-shaped member 55, which pocket is provided with a port, or series of ports 56, through which the liquid therein passes to the base of the chamber and thence out through the apertures 52. It will be noted that the drain 43, 65 70 75

shown in Figs. 1 and 2, is unnecessary in the modification illustrated in Fig. 4.

By means of my improved apparatus, I not only obtain absolute uniformity of mulling but I am enabled greatly to reduce first cost by providing a mulling box having minimum of cubical contents for a given quantity of material to be treated and operated by a low-power impeller costing much less than the high-power blower which is necessary for forcibly directing humidified air into contact with the material, and also to reduce the operating costs by virtue of the comparatively small amount of energy required to actuate the motor and the heating unit, a relatively small heating unit sufficing on account of the practically negligible heat loss.

Having thus disclosed illustrative embodiments of my invention whereby material may be conditioned, without however limiting myself thereto, what I claim and desire to secure by Letters Patent is:

1. Apparatus for conditioning material comprising in combination a chamber, a hollow member affording a duct disposed centrally within said chamber and terminating short of oppositely-disposed walls thereof, means for supporting the material to be treated in said chamber, an open liquid-container disposed in the vicinity of said duct, and means for moving a stream of air along the surface of a liquid in said container and for directing the same through said duct.

2. Apparatus for conditioning material comprising in combination a chamber, a hollow member affording a duct disposed centrally within said chamber and terminating short of oppositely-disposed walls thereof, means for supporting the material to be treated in said chamber, an open liquid-container disposed in the vicinity of said duct, and an impeller disposed in co-operative relation with said duct and container.

3. Apparatus for conditioning material comprising in combination a chamber, a hollow member affording a duct disposed centrally within said chamber and terminating short of the top

and bottom thereof, means for rotatably mounting said hollow member, material-supporting means secured to and projecting from said hollow member, means for humidifying the air in said chamber, and means for directing a current of such humidified air through said duct.

4. Apparatus for conditioning material comprising in combination a chamber, an open liquid-container disposed within said chamber, means for moving a stream of air along the surface of a liquid in said container, a gutter constructed and arranged to receive all of the liquid condensation formed on the upper wall of said chamber and a conduit connecting said gutter to said container.

5. Apparatus for conditioning material comprising in combination a chamber, a hollow member affording a duct disposed within said chamber and terminating short of the top and bottom thereof, means for humidifying the air in the upper portion of said chamber, a baffle located at the lower end of said duct and extending toward the walls of said chamber, and an impeller disposed above the upper end of said duct.

6. Apparatus for conditioning material comprising in combination a chamber, a hollow member affording a duct disposed within said chamber and terminating short of the top and bottom thereof, an open liquid-container disposed above the upper end of said duct, a baffle located at the lower end of said duct and extending toward the walls of said chamber, and an impeller disposed above the upper end of said duct.

7. Apparatus for conditioning material comprising in combination a chamber, a hollow member affording a duct disposed centrally within said chamber and terminating short of oppositely-disposed walls thereof, means for supporting the material to be treated in said chamber, means for humidifying the air in said chamber, a baffle located at one end of said duct and extending toward the walls of said chamber, and an impeller disposed in co-operative relation with said duct.

ELMER C. INGRAHAM.
